UNITED STATES PATENT OFFICE.

FREDERICK GEIGER, OF CLEVELAND, AND GEORGE C. SWIFT, OF CLEVELAND HEIGHTS, OHIO, ASSIGNORS TO THE ENAMEL PRODUCTS COMPANY, OF CLEVELAND, OHIO, A CORPORATION OF OHIO.

MACHINE FOR FORMING FLANGES.

Application filed February 16, 1925. Serial No. 9,538.

The present invention relates to a machine for forming flanges on sheet metal articles such as table tops, wash-tub covers, dirt trays, broiler pans and the like, which require a rebent, or turned underneath flange around the edge. More particularly the present machine, as shown, is adapted for turning in the rebent flanges of table tops such as are made into enamel table tops and has for its object the forcing of the rebent flanges at the corners of the tops at the same time that the side flanges are formed. In such rebending operation it is necessary to provide against shearing or breaking the flanges, particularly at the corners where the metal must be smoothly bent.

To the accomplishment of the foregoing and related ends, said invention, then, consists of the means hereinafter fully described and particularly pointed out in the claims.

The annexed drawing and the following description set forth in detail certain mechanism embodying the invention, such disclosed means constituting, however, but one of various mechanical forms in which the principle of the invention may be used.

In said annexed drawing:—

Fig. 1 is a top plan view of the machine; Fig. 2 is a central vertical longitudinal section taken on the line 2—2 of Fig. 1; Fig. 3 is a transverse sectional view taken on the line 3—3 of Fig. 1; Fig. 4 is a section of a portion of the device shown in Fig. 2 but showing the forming members in their closed position; Fig. 5 is a section on the line 5—5 of Fig. 1; and Fig. 6 is a plan view of the pusher plate.

The machine comprises a base formed of two main side rails 1 connected together by means of a bed plate 2. At the right hand end of the machine as seen in Figs. 1 and 2, there is mounted in bearings 4 the main driving or power shaft 5 which, as shown, has tight and loose pulleys 6 and 7 thereon. Near one end there is mounted a small spur gear 8 in mesh with a large gear 9 mounted on a second or driven shaft 10 carried in bearings 11 on the side rails. This shaft is provided on each end with a driving wheel 12 having crank pins 13 thereon. These pins have cranks or connecting rods 14 mounted thereon and connected at their

ends to a cross shaft 15 carried in bearings 55 16 mounted in bearing brackets 17 secured to the cross head or slide 18 of the machine.

This cross head or slide consists of a heavy member suitably mounted in slide-ways 20 mounted on the bed plate 2 and is 60 movable forward and back by the cranks 14.

The forming devices consist of a fixed member 25 of V-shape, the legs 26 extending at 90° to receive the corner of a rectangular table top 27 which is to be flanged. 65 The base of the V is rounded to the curvature which it is desired to give the table corner. This die member is stationary and is spaced above the bed plate and has its forward edge curved or rounded off as at 70 28 so as to bend and form the desired flange and not shear the same.

Between the stationary die and the bed plate is mounted a pusher plate or extractor 29 roughly Y-shaped as best shown in Fig. 6 and having its tongue or leg 30 extending rearwardly and terminating at the edge of a slot 31 in the bed. This pusher plate is normally in the position indicated in Fig. 2 and is resiliently held there by means of a rocker arm 33 mounted on a cross shaft 34 carried in the side rails and normally rocked by means of springs 35 connected to the side rails and to arms 36 depending from the rock shaft. 85

The moving die or forming member comprises a V-shaped die member 40 carried by an extending arm 41 connected to the cross head by means of the bolts 42 so as to be movable therewith. The V-shaped member is removably attached to the tongue by bolts or screws 43 or the like and may be changed for different size table tops. In operating the machine, the operator places a table top 27, or other article to be formed, which has previously been formed with a flange 51 around its edge bent at an angle to the plane of the top underneath and snugly against the movable die member 40 with the flange extending upwardly and with a corner of the top at the point of the die member. As the cross head moves, drawing the die member 40 to the right, the table top flange 51 is first moved against the pusher plate or extractor 29 and then with the latter underneath the stationary member 25 with the curved face until it reaches the position shown in Fig. 4 at which time 100 105

the upper portion of the flange 51 is rebent inwardly of the table top and parallel thereto. This movement forces the pusher plate 29 back and rotates the rock shaft 34 to the position shown in Fig. 4. When the moving die 40 is retracted to its normal position shown in Fig. 2, the pusher plate 29 is moved out by the action of the springs 35 and the table top is thus forced out from under the stationary die.

The dies for a table top, such as is illustrated in the drawings, are of such a size as to form the corner and slightly more than one half of each side adjacent the corner. 15 As soon as the die is retracted and the table top freed from the stationary die, the operator shifts the top 90° presenting the next corner to the movable die and the operation is repeated. Each top is thus formed four 20 times, one for each corner and when thus formed is completed with an inwardly bent flange 55 around its entire edge and is made ready for the enamelling or finishing operations.

25 The length of the sides of the die members will be varied to suit the size of table tops or other articles being operated upon. As the operator merely has to turn and remove and position the articles the forming 30 may proceed rapidly. The curved stationary die bends the flange 55 gradually both at the corner and along the sides and does not break or shear the same, thus eliminating this particular difficulty, particularly at the corner 35 proper which is slightly rounded and in which the entire metal must be reformed slightly during the bending operation. The dies are removable mounted so that dies for various sizes or different articles may be inserted in 40 the machine, it being understood that any regular sided article, such as a boiler pan, washer cover or the like, may be formed as readily as a table top such as has been illustrated. In rounded or circular objects the 45 two dies will be of a size to finish up to a half top, as in the case of a circular article, or if the article is irregular in shape, a portion of the flanging may be done and then the dies changed for the rest of the flanging 50 operation.

Other modes of applying the principle of our invention may be employed instead of the one explained, change being made as regards the mechanism herein disclosed, provided the means stated by any of the following claims or the equivalent of such stated means be employed.

We therefore particularly point out and distinctly claim as our invention:—

60 1. In a rebent flange forming machine, the combination of a base, a movable slide thereon, a stationary die member removably mounted on said base, said member being shaped to fit a predetermined portion of the edge of the article to be formed, a comple-

mentary shaped die member slidably and removably mounted on said base and adapted to be operatively connected to said movable slide, said member being adapted to receive a partially formed article having a flange 70 and to move such article under said stationary die member to form a rebent flange thereon over a predetermined edge extent and guide means on said stationary die for maintaining the slidable complementary die 75 in alignment.

2. In a rebent flange forming machine, the combination of a base, a movable slide thereon, a stationary die member removably mounted on said base, said member being shaped to fit a predetermined portion of the edge of the article to be formed, a complementary shaped die member slidably and removably mounted on said base and adapted to be operatively connected to said movable slide, said member being adapted to receive a partially formed article having a flange and to move such article under said stationary die member to form a rebent flange thereon over a predetermined edge extent, a 80 guide on said stationary die for maintaining the slidable complementary die in alignment, and extractor means movably mounted on said base under said stationary die member for ejecting the article after the forming 85 operation.

3. In a rebent flange forming machine, the combination of a base, a movable slide thereon, a stationary die member removably mounted on said base, said member being adapted to fit a predetermined portion of the edge of the article to be formed, a complementary shaped die member slidably and removably mounted on said base and adapted to be operatively connected to said movable slide, said member being adapted to receive a partially formed article having a flange and to move such article under said stationary die member to form a rebent flange thereon over a predetermined edge extent, a guide on said stationary die for 100 maintaining the slidable complementary die in alignment, and an extractor plate movably mounted on said base under said stationary die member and normally resiliently held in article ejecting position but being adapted to move with said movable die member during the forming operation.

4. In a rebent flange forming machine, the combination of a base, a movable slide thereon, a stationary die member removably mounted on said base, said member being adapted to fit a predetermined portion of the edge of the article to be formed, said member having its lower edge curved to produce a beveling action without shearing, a guide on said stationary die, an arm extending from the aforesaid slide through said guide, a complementary shaped die member removably mounted on said arm connected 110 115 120 125 130

- to said movable slide, said member being adapted to receive a partially formed article having a flange and to move such article under said stationary die member to form a rebent flange thereon over a predetermined extent, and extractor means movably mounted on said base under said stationary die member for ejecting the article after the forming operation.
- 10 5. In a rebent flange forming machine, the combination of a base, a movable slide thereon, a stationary die member of V-shape mounted on said base and spaced above the same, a guide on said stationary die, an arm extending from the aforesaid slide through said guide, and a complementary V-shaped die member movably mounted on said arm connected to said movable slide, said movable die member being adapted to receive a 15 partially formed rectangular article and to move the same under said stationary die to form a rebent flange thereon at the corner on approximately one half of each adjacent side.
6. In a rebent flange forming machine, the combination of a base, a movable slide thereon, a stationary die member of V-shape mounted on said base and spaced above the same, a guide on such stationary die, an arm extending from said slide through the said 20 guide, a complementary V-shaped die member removably mounted on said arm connected to said movable slide, said movable die member being adapted to receive a partially formed rectangular article and to move the same under said stationary die to form a rebent flange thereon at the corner on approximately one half of each adjacent side, an extractor plate movably mounted on said base under said stationary die member and adapted to eject the formed article from said stationary die upon retraction of said 25 movable die, and a spring actuated rock shaft and rocker arm in contact with said extractor plate and adapted to return said plate to its normal table top ejecting position.
7. In a rebent flange forming machine, the combination of a base, a movable slide thereon, a stationary die member of V-shape mounted on said base and spaced above the same, a complementary V-shaped die member movably mounted on said base and connected to said movable slide, said movable die member being adapted to receive a partially formed rectangular article and to move the same under said stationary die to form a rebent flange thereon at the corner on approximately one half of each adjacent side, an extractor plate movably mounted on said base under said stationary die member and adapted to eject the formed article from said stationary die upon retraction of said movable die, and a spring actuated rock shaft and rocker arm in contact with said extractor plate and adapted to return said plate to its normal table top ejecting position.
8. In a rebent flange forming machine, the combination of a base, a movable slide thereon, a stationary die member of V-shape mounted on said base and spaced above the same, said member having its lower top contacting edge rounded off to bend the flange without shearing action, a guide on said stationary die, an arm extending from said slide through the said guide, and a complementary V-shaped die member removably mounted on said arm connected to said movable slide, said movable die member being adapted to receive a partially formed rectangular article and to move the same under said stationary die to form a rebent flange thereon at the corner on approximately one half of each adjacent side.
9. In a rebent flange forming machine, the combination of a base, a movable slide thereon, a stationary die member of V-shape mounted on said base and spaced above the same, said member having its lower top contacting edge rounded off to bend the flange without shearing action, a complementary V-shaped die member removably mounted on said base and connected to said movable slide, said movable die member being adapted to receive a partially formed rectangular article and to move the same under said stationary die to form a rebent flange thereon at the corner on approximately one half of each adjacent side.
10. In a table top forming machine, the combination of a base, a power shaft mounted therein, a cross head slidably mounted on said base, driving connections from said power shaft to said cross head adapted to reciprocate the latter, a stationary die member of V-shape having a rounded angle secured on said base and spaced above the same, a guide on said stationary die, an arm extending from said crosshead through the said guide, an extractor plate of V-shape slidably mounted on said base under said stationary die member, resilient means for normally holding and returning said extractor plate to its table top ejecting position, and a movable die member of V-shape mounted on said arm connected to said cross head to be reciprocated thereby, said movable die member being adapted to receive a partially formed table top and move the same under said stationary die to form a rebent flange at the corner and along approximately one-half of each adjacent side.
11. In a table top forming machine, the combination of a base, a power shaft mounted therein, a cross head slidably mounted

on said base, driving connections from said power shaft to said cross head adapted to reciprocate the latter, a stationary die member of V-shape having a rounded angle secured on said base and spaced above the same, said die member having a curved lower edge to bend the table top flange without shearing, a guide on said stationary die, an arm extending from said crosshead through the said guide, an extractor plate of V-shape slidably mounted on said base under said stationary die member, a spring actuated rocking arm for normally holding

and returning said extractor plate to its table top ejecting position, and a movable die member of V-shape mounted on said arm connected to said cross head to be reciprocated thereby, said movable die member being adapted to receive a partially formed table top and move the same under said stationary die to form a rebent flange at the corner and along approximately one-half of each adjacent side.

Signed by us, this 6 day of Feb., 1925.

FREDERICK GEIGER.
GEORGE C. SWIFT.
